UNITED STATES PATENT OFFICE.

ANDRÉ VARAUD, OF GENEVA, SWITZERLAND.

APPARATUS FOR TIMING CLOCKWORK-OPERATED MECHANICAL FUSES FOR ARTILLERY PROJECTILES.

Application filed June 2, 1926, Serial No. 113,167, and in Switzerland June 3, 1925.

The object of the invention is an apparatus for timing the clockwork operated mechanical fuses for artillery projectiles of the type as described in the United States 5 patent application Serial No. 712,960 and in which the winding of the driving spring of the clockwork and the regulation of the time for exploding the projectile is effected simultaneously by turning a key arranged in 10 the axis of the point of the fuse by means of a timing apparatus, and of the type in which said key is adapted to describe several revolutions in order to obtain the maximum duration of the working of the fuse.

15 This apparatus, which may be designed to either time each projectile individually or for timing simultaneously several of them, is characterized by the fact, that it embodies at least a rotary timing member, that 20 is to say for turning a key, rotating a screw nut the course of which on an externally threaded member rigidly fixed to the fuse body during the timing operation, is limited on the one hand by a stop carried by 25 said threaded member, and on the other hand by a stop fixed rigidly on an internally threaded member adapted to cooperate with a threaded portion of the externally threaded member, the relative angular 30 displacement of the two members being adjustable for a fraction of a rotation with regard to a helicoidal graduation provided on one of them and means being provided for blocking said two members together in 35 any predetermined adjusting position.

The drawing shows by way of example a working form of an apparatus adapted for timing each projectile individually, one after the other.

40 Fig. 1 is an elevation showing the nut and also the operating handle arrested or blocked in the position "0" of the apparatus.

Fig. 2 is an axial section made on the line II—II of Fig. 1 and showing the apparatus 45 in the same position as in Fig. 1.

Fig. 3 is also an axial section on the line II—II showing the apparatus adapted to a fuse and adjusted for effecting the setting of the same for the maximum time available.

50 It is seen in the drawing that the winding and the simultaneous regulating key A of a fuse A¹ is rigidly connected by means of a tenon c with a shaft a of the operating handle b whenever the tube body d of the 55 apparatus is angularly arrested by means

of a tenon A² on the fuse A¹ as shown in Fig. 3. In this manner it is possible to directly rotate the key A by means of the handle b.

The timing shaft a is provided with a 60 square portion e carrying a drum f having a slit g cooperating with a stop h projecting from the periphery of the nut i referred to in the claims. Owing to this arrangement, the nut is screwed or unscrewed from a 65 threaded portion k of the body d whenever the handle b is operated.

The possible angular displacement of this nut i,—which is zero as represented in Figs. 1 and 2,—is limited on the one hand by the 70 fixed stop l rigidly connected with the body d when a stop m projecting from the top face of the nut i comes to strike against stop l, and on the other hand by an adjustable stop n when a second stop o projecting laterally from the bottom of the nut comes to meet the former stop. The stop n is arranged on a threaded and split ring p, the position of which on a second threaded portion k¹ of the body d may be adjusted with 75 regard to a helicoidal graduation r marked on the body d. This ring p may be arrested in whatever predetermined adjusting position by means of a screw key s so that the movable stop n is fixed to the body d 80 of the apparatus.

The handle b is frictionally mounted on the shaft a in order to prevent that the stops n and o may become subjected to too violent shocks if, at the end of the timing 90 operation, too strong an impulse is given to said handle.

The divisions of the graduation may either refer to seconds and fractions of seconds indicating the time in which the explosion 95 of the projectile is effected, or to kilometers and meters indicating the range of the firing.

The apparatus described works as follows:

If the movable members of the apparatus 100 are in their arrested position as represented in the Figs. 1 and 2, the apparatus will first have to be adjusted by unscrewing the key s and by rotating the ring p by hand until the index provided on said ring comes opposite 105 the predetermined division of the helicoidal graduation r. Thereupon the key s is again screwed tight in order to immobilize the adjustable stop n in its regulating position. Now the apparatus is ready for timing a 110

single projectile or a number of them one after the other according to the predetermined time interval.

Each one of these operations for timing a fuse is composed as follows:

1. Fixing of the apparatus on the fuse A^1 in such a manner that any angular displacement of the body d is prevented by the tenon A^2 and that the tenon c enters in the slit of the key A .

2. The handle is rotated until the lower stop o of the nut strikes against the adjustable stop n .

3. The apparatus is withdrawn from the timed projectile.

4. The handle is returned in the opposite direction in order to bring the top stop m of the nut to bear against the fixed stop i .

The fixed body of the apparatus might be constituted by a member rigidly connected with the split ring p . In this case the adjusting of the apparatus would be effected by rotating the tubular body d and the stop l would then become the adjustable stop. The fixed stop would be constituted by the stop n and the timing operation would remain the same as in the example described above.

Several timing shafts a might be provided which are operated by means of bevelled gears and a single handle b so as to allow to simultaneously adjust a plurality of projectiles for the same time interval to explosion.

It would finally be possible to provide means, such as a spring, in order to automatically return the handle b in its initial position after each complete timing operation or to provide a safety device preventing the beginning of a new timing operation if it has been neglected to return the handle by hand in its initial position.

I claim:

1. Apparatus for timing clockwork operated mechanical fuses for artillery projectiles, fuses of the type in which a key, arranged in the point of the fuse when being

turned by means of a timing apparatus, is adapted to simultaneously wind the driving spring of the clockwork and to regulate the time of the explosion of the projectile, and further of the type in which said key may be made to perform several revolutions in order to effect the timing for the maximum duration of the working of the fuse, said fuse comprising a rotary member for timing arranged in such a manner as to rotate when being turned, a nut whose course on an externally threaded member is limited on the one hand by a stop carried by said threaded member and on the other part by a stop fixed to an internally threaded member adapted to cooperate with said internally threaded member which, during the operation of timing the fuse, is rigidly connected with the fuse body, the arrangement being such that the rotary angular displacement of the two threaded members may be adjusted for a fraction of a turn with regard to a helicoidal graduation provided on one of the said threaded members, and means being at disposal for rigidly uniting and arresting these two threaded members in their predetermined regulating position.

2. Apparatus as per claim 1 in which the internally threaded member is constituted by a split ring adapted to be immobilized by a screw key in the manner of a circular clamp arranged on the second threaded portion of an externally threaded member constituting the body of the apparatus.

3. Apparatus as per claim 1 in which the internally threaded member is constituted by a split ring adapted to be immobilized by a screw key in the manner of a circular clamp arranged on the second threaded portion of an externally threaded member constituting the body of the apparatus, and in which each rotary member for timing is fixed rigidly to a drum provided with a slit in which a stop projecting from the periphery of the nut is adapted to become operative.

In testimony whereof I affix my signature.

ANDRÉ VARAUD.
